Lacy Lacy, Attorney

UNITED STATES PATENT OFFICE.

FRANK MATOUSHEK, OF COLOME, SOUTH DAKOTA.

ADJUSTABLE RATCHET WRENCH.

Application filed June 2, 1924. Serial No. 717,331.

To all whom it may concern:

Be it known that I, FRANK MATOUSHEK, a citizen of the United States, residing at Colome, in the county of Tripp and State of 5 South Dakota, have invented certain new and useful Improvements in Adjustable Ratchet Wrenches, of which the following is a specification.

My invention relates to an adjustable wrench provided with a ratchet device for 10 operating the same, said ratchet device being reversible so that the wrench may be used both for right and left hand work.

The wrench is provided with gripping 15 jaws which may, by a simple operation, be set to accommodate a bolt head or nut of any size and these jaws have positive movement toward and away from each other so that the adjustment of the wrench after 20 having been set to a certain sized nut, for instance, will remain constant until the wrench is reset.

In the accompanying drawing one embodiment of the invention is illustrated and:

25 Figure 1 is a top plan view of the wrench, Figure 2 is a section along line 2—2 of Figure 1,

Figure 3 is a section along line 3—3 of Figure 2,

30 Figure 4 is a section along line 4—4 of Figure 2, showing one of the jaws, and

Figure 5 is a view illustrating the sleeve employed for guiding the jaws.

In the drawing, the reference numeral 10 represents a handle which is preferably made from suitable wire or metal rod bent double to form handle shanks extending substantially parallel to each other and provided at their ends with inturned grippers 11. These grippers are cone-shaped and preferably provided with knurled surfaces, and are arranged in axial alinement, as best shown in Figure 3. The shanks of the handle 10 are held rigidly together by means 45 of a transverse bolt 12 threaded in one of the shanks and secured by a lock nut 13.

The reference numeral 14 represents the head of the wrench, which head is provided with a lug 15 on one side thereof. This lug 50 has axially alined sockets 16 corresponding to the grippers 11 of the handle and when the grippers are inserted in the sockets 16 and the bolt 12 is tightened, the handle has a firm grip on the head and may be set at 55 a suitable angle for doing the work, and it

is evident that the handle may be turned up or down in relation to the head.

The head 14 has a cylindrical bore 17 in which snugly but revolvably fits a sleeve 18. This sleeve has a collar 19 at one end adapted to abut against the top surface 20 of the head and a narrow neck 21 projecting through the under side of the head, as best seen in Figure 2. Around the lower edge of this neck 21 is provided a number of T-slots 22 adapted to engage in correspondingly shaped guide arms 23 on the jaws 24. These guide arms are arcuate, as best seen in Figure 2, extending inwardly in the bore of the head 18, and have their inner ends 25 pivoted within an adjusting plug 26. The plug is ring shaped and is provided with external threads adapted to engage corresponding threads 27 in an adjusting nut 28. This nut 28 is revolvably mounted in the sleeve 18 and engages with its collar 29 the collar 19 of the sleeve. The nut is slightly longer than the sleeve 18 so as to permit the jaws 24 to work freely within the sleeve without interference by the nut.

The outer ends of the jaws 24 are provided with gripping fingers 30 set substantially at right angles to the lower ends of the guide arms 23. It will now be evident that by turning the nut 28 in the sleeve 18, the adjusting plug 26 may be advanced or retracted in the nut, at the same time pushing out or drawing in the pivoted ends 25 of the jaws to open or close the fingers 30. It will now also be seen that when the adjusting plug 26 travels downwardly, the T-slots 22 in the sleeve 18 will cooperate with the arcuate guide arms 23 of the jaws to spread the gripping fingers 30 of the latter apart and that the opposite takes place when the adjusting plug 26 travels upwardly in the nut.

The sleeve 18 is provided with an annular groove 31 in which ratchet teeth 32 are furnished and these ratchet teeth are adapted to engage with a ratchet dog 33 housed in the lug 15 of the head 14. This dog is seated substantially in the medial plane of the head 14 and has a stem 34 around which a coiled spring 35 is disposed. This spring is housed in a chamber 36 provided in the lug 15, one end of the spring abutting against the collar 37 on the stem 34 and its other end abutting against a closing cap 38 for the chamber 36. On the outer end of 110

the stem 34 of the dog 33, is provided a yoke 39 straddling the lug 15 by means of short arms 40. The relative length of the arms 40 is such that the dog can be lifted 5 out of engagement with the ratchet teeth 32 and turned one hundred and eighty degrees in its seat. The slanting surface of the nose of the dog will thus be presented opposite to its first position and the teeth 32 of the 10 sleeve 18 being square on both sides, this will permit reversal of the operation of the handle to the first position of the ratchet dog 33.

The dog holds the revoluble member 18 stationary relative to the head during the 15 working stroke of the handle but permits the head to revolve upon the said member during the return stroke of the handle, the jaws 30, of course, through their engagement with the work preventing relative 20 movement of the hollow annular plug and the revoluble member 18. After the hollow annular plug 26 has been set through the application of any turning tool so as to properly adjust the jaws, the engagement of 25 said plug with the sleeve nut 29 performs the function of a lock nut to hold the parts in the position in which they have been set so that the adjustment of the jaws will not be disturbed.

30 According to the number of gripping jaws 24 provided in the head, the wrench may be used on square, hexagonal, or other shaped nuts. In the drawing, four jaws have been shown which are accordingly adapted to engage a square nut, while for a hexagonal nut, six jaws would have to be provided.

Having thus described the invention, what I claim is:

1. An adjustable wrench comprising a

head, a handle on said head; a revoluble member in said head provided with ratchet teeth, a dog in said head engaging said teeth, gripping jaws, and means for adjusting the gap of said jaws; said means including arms on said jaws engaging corresponding guide elements at the lower end of said revoluble member, a sleeve nut revolubly mounted in said member, and a hollow annular plug having threaded engagement with the interior of said sleeve nut and having said arms pivoted to the inner circumference. 40 45 50

2. An adjustable wrench comprising a head, a handle on said head, a revoluble member in said head provided with ratchet teeth, a dog in said head engaging said teeth, gripping jaws, and means for adjusting the gap of said jaws, said handle having shanks terminating with inwardly extending grippers engaging in corresponding sockets 55 60 in said head, said grippers being tapered and having serrated surfaces.

3. An adjustable wrench comprising a head, a handle on said head, a revoluble member in said head provided with guide 65 slots in its lower end, means in the head for rotating said member, gripping jaws, arms on said jaws slidably engaging the guide slots in said revoluble member, a sleeve nut revolubly mounted in said member, and a 70 hollow annular plug having threaded engagement with the bore of said nut, the arms on the jaws having their upper ends pivoted to the inner circumference of the plug. 75

In testimony whereof I affix my signature.

FRANK MATOUSHEK. [L.S.]
